UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

LOAD-DISCHARGING CAR.

Original application filed August 31, 1922, Serial No. 585,431, now Patent No. 1,465,756, dated August 21, 1923. Divided and this application filed August 13, 1923. Serial No. 657,058.

To all whom it may concern:

Be it known that I, ARGYLE CAMPBELL, a citizen of the United States, residing at Chicago, in the county of Cook and State of Illinois, have invented a certain new and useful Improvement in Load-Discharging Cars, of which the following is a full, clear, concise, and exact description, reference being had to the accompanying drawings, forming a part of this specification.

This application is a division of my co-pending application for load discharging cars, Serial No. 585,431, filed August 31, 1922, since become Patent 1,465,756, granted

15 Aug. 21, 1923.

This invention relates to improvements in load discharging cars and more particularly to the type known as "ballast cars" used in the construction and maintenance of railroads and provided with a central hopper for dumping between rails and convertible for use as a gondola or for side dumping with top unloading plow.

The primary object of my invention is to 25 provide a center dumping car which will discharge its load centrally of the roadbed and avoid flooding the rails.

A further object of the invention is to improve the structural design of this type 30 of car by combining strength and rigidity of the parts with economy of material and more especially in regard to the framework adapted to withstand the shocks incidental to buff and draft.

Another object of the invention is to provide a center dumping car which will discharge its load uniformly and wherein the flow of ballast will be under perfect control of the operator at all times.

It is also the object of the invention to 40 provide for greater cubical capacity as a hopper car than has heretofore been possible with a given length of door opening.

My invention also resides in certain other 45 features of novelty which will be more fully described in the specification and claims.

In the drawings forming a part of this specification, Figure 1 is a vertical sectional view taken transversely of the car near the center thereof showing the offset construction of the hopper and the position of the convertible floor sections when the car is

adapted for use as a center dump car. Figure 2 is a top plan view of a portion of the car hopper extending from one end thereof to the center of the car. Figure 3 is a longitudinal, sectional view of the car as a hopper showing slightly less than a half thereof, the section being taken to one side of the center of the car. Fig. 4 is an end elevational view of one half of the car showing the movable end at one end of the car in position for use as a gondola car. Figure 5 is a sectional view of the car taken substantially on the line 5—5 of Figure 4, showing the disposition of the sloping floor member when the end is in position as a gondola car. Figure 6 is a transverse partial sectional view taken on line 6—6 of Figure 2 of the car door raising and lowering mechanism with the front housing removed exposing the worm and gear mechanism. And Figure 7 is a view taken on the line 7—7 of Figure 6 showing the side of the car with the actuating mechanism for operating the worm and gear.

Referring now to the drawings wherein like characters indicate the same parts, it will be seen that the car consists of a framework composed of heavy longitudinal side 80 sills A and intermediate longitudinal sills B and transverse members comprising end sills C; body bolsters D, cross ties E. Non continuous draft sills F are centrally disposed at each end of the car and diagonal 85 members G extend obliquely to the line of the draft and connect to the longitudinal sills near the body bolsters. A longitudinal hopper is disposed between the intermediate sills and one side thereof consists of an upper stationary inclined floor H to which the swinging door J is pivoted while the opposite side thereto is composed of an inclined stationary floor K. The hopper is formed at each end with an inclined wall 90 L resting on the draft sills and secured to the stationary inclined side walls of the hopper. Swinging convertible floor portions M are disposed to each side of the hopper forming a continuation of the hopper side walls of the car above the floor. The ends of the car above the floor line consist of movable portions N with inclined 95 shedding members O. The side walls are

composed of vertical stakes P, top rail R and swinging side doors S.

Having now given a general description of the car, I will proceed to describe with 5 particularity the various features involved in my invention.

Intermediate sills B consist of web plates 17, outer bottom angles 18 and inner bottom angles 19, top Z-bar members 20 and 10 outer top angles 21. The top flange of the Z-bar 20 extends over the angle 21, thereby sealing the joints between the web plate and sill top members and preventing the entry of moisture and corrosive influences 15 therebetween. The upper surface (20^a) of the Z-bar forms a portion of the floor of the car and a runway for the plow protecting the rest of the floor of the car from the destructive effects of the unloading 20 top plow. Side sills A composed of web plates 22, top angles 23, and bottom angles 24, extend the full length of the car and are caused to function in unison with the intermediate sills as load carrying members 25 by means of diaphragms 25, top cover plates 26, and bottom cover plates 27 disposed near the bolsters and secured to both of the said sills. A number of cross ties E, preferably of channel shape, extend between the intermediate sills and are secured thereto by means of gussets 28.

The inclined side floor H of the car comprises end plates 29 and intermediate plates 30 secured to a longitudinally extending 35 angle 31, the latter passing beneath cross ties and secured to the latter and also to the end hopper sections 48. The upper portions of plates 29 and 30 respectively are formed with horizontal ledges 29^a and 30^a 40 adapted to rest on the lower horizontal flange of Z-bar 20 and secured thereto, thereby presenting an extension of the Z-bar flange of sufficient width to support the convertible floors in both their inclined 45 and horizontal positions. The intermediate floor plates 30 are flanged upwardly as at 30^b for the purpose of effecting a connection with the cross ties E while the other end of the plates as at 29^c and 30^c 50 respectively are provided with holes whereby riveted connections are effected between these ends and the cross ties by means of members 320 when the structure as composed of members 29, 30 and 31 has been 55 fitted into place on the car. Door supporting brackets 32 are riveted to this inclined structure and it should be stated at this time that the construction as adopted herein favors quantity production inasmuch 60 as the whole side as shown may be assembled as a unit thereby assuring alignment of the hinges and afterwards quickly fitted into place on the car structure. The gussets 28 are shaped as at 28^a, in order 65 that they may be contained beneath the

floor instead of passing therethrough and causing unwieldy and insecure connections between the various parts as has heretofore been the case. Diaphragms 33 support the floor intermediately of the cross ties and are riveted or otherwise secured to the floor plates as at 29^d and 30^d. Connection between each diaphragm and angle 31 is effected by means of a gusset plate 34. In this manner, it will be seen that I have provided an upper stationary floor section of great strength and simplicity and furthermore one which presents an unbroken shield for the door, thereby preventing the entry of small rocks between the inclined 70 floor and door at the hinge location.

The opposite side "K" of the hopper section is formed of a series of sloping side sections 35 extending downwardly and inwardly from the intermediate sill B towards the longitudinal center of the car. The lower edge of the side "K" terminates in a plane disposed to one side of the longitudinal central plane of the car. The edge terminates on the same side of the central plane as that on which the side "K" is located. Said free edge of the sloping side "K" is reinforced by a Z-bar 36. The purpose of this latter member is two-fold, acting as a beam to strengthen the floor plate and also having the lower flange thereof constituting a material shield to guard the rail from being flooded by the ballast material. This shield as will be noted from Figure 1 has the controlling point 36^a thereof located a distance from the longitudinal center of the car. The sloping floor sections are formed at their upper portions with ledges 35^a, and connections with cross ties E are made by means of connections 37 and stiffening angles 38. The floor near its free ends is supported from the cross ties by means of tension plates 39. Intermediate of the cross ties the sloping plates are supported by means of angles 40 and braced to intermediate sills by means of gusset plates 41 and vertical stiffeners 42 in the manner shown in Figure 2. The end walls "L" 100 of the hopper rest on the draft sills formed of web plates 420, top angles 43 and bottom angles 44. Each sloping end wall proper consists of a trapezoidal shaped plate 45 bent to form a horizontal floor 45^a and also a vertical wall 45^b. The horizontal portion 105 45^a is secured to the top members of the intermediate sills and stiffened with angle bars 46 between supports. Connection between the draft sills and the inclined floor 110 is made by means of angles 47. The completion of the hopper proper is made by triangular shaped sections 48 and 49 respectively which connect the side and end sloping floors thereby producing a perfect self 115 discharging hopper. An angle 50 connects 120 125 130

the vertical hopper end wall 45^b with sloping floor plate 35.

Referring now to the hopper door "J", this member is preferably formed to operate 5 as a single unit although it may be manufactured in sections. In its preferred form it consists of a plate 51 having one end flanged as at 51^b and slotted at 51^c for the passage of hinge straps 52 therethrough. These 10 hinge straps are preferably riveted to the door plate in connection with reinforcing angles 53 which extend down to and are anchored to stiffener 54 which preferably consists of a bulb angle and extends the 15 length of the door. The door is formed to extend beneath the hopper end walls, thereby ensuring a tight joint when the door is closed and adjacent to the edge of the door at each end of the car, I have disposed an 20 end wall or shield 55 to avoid the escape of material from the car between the edge of the door and the sloping floor section 48 and the lower edge of the hopper end wall 45^b. This shield is braced by means of a 25 rearwardly extending vertical gusset 56 which is secured to the draft sill angle and to the shield. This shield is further secured to the end wall by means of angle 57 and also to the Z-bar member 36. The door "J" 30 is adapted to swing on its pivot 57' from hinge bracket 32 and close the door opening. Chains or other flexible elements 58 are disposed at suitable intervals and attached to the door by means of brackets 59, passing 35 through holes 36^b formed in the web of Z-bar member 36 and attached to sheave members 60. The sheaves are rigidly mounted on a shaft 600, preferably of polygonal shape, adapted to rotate in bearings 61 which are secured to the car structure. 40 The sheaves are preferably formed eccentric in order to reduce the leverage or twisting moment on the shaft when the doors are closed and the car is loaded. Collars 45 62 are mounted on the shaft in order to provide a uniform bearing in brackets 61. The bearings 61 are preferably anchored to the gussets 28 connecting the cross ties E to the intermediate sills, but towards the end 50 of the hopper provision is made for supporting the shaft from the floor supporting gusset 41. The doors are opened and closed by means of gearing, preferably enclosed in a dust and oil proof housing formed of 55 a plurality of sections 63 and 64. These sections are bolted or riveted together and in Figure 6 I have shown the interior view of the mechanism with outer casting 64 removed showing the gears 65 and the worm 66. The gear 65 is rigidly secured to shaft 600 and is preferably disposed intermediate 60 of some of the sheaves in order that the twisting moment on the shaft may be distributed on either side of the gear. Housing 65 section 63 is provided with bracket portions

63^a whereby the housing is secured to the car structure preferably at one of the cross ties E and below the sloping floor and adjacent to the intermediate sill. For this purpose I provide an enlarged gusset 67 of the same 70 type as hereinbefore designated as 28 and provide connecting angle 68 between the sloping floor and this gusset. A driving shaft 69 is rigidly secured to the worm gear 66 and passes through the intermediate and side sills through a combined reinforcing and ratchet plate 70. This plate, which is 75 securely riveted to the side sill web to reinforce this member and compensate for the hole made therein, has a bearing for ratchet 71 and also provides pivotal bearings for pawl 72 and dog 73. Actuating mechanism is 80 provided by the lever handle 74 which carries pawl 75 whereby the ratchet 71 is engaged. Pawl 75 is held into engagement 85 with the ratchet by means of plunger 76 and spring 77.

Reference to Figure 1 will show that the apex of the hopper when the door is closed is disposed to one side of the longitudinal 90 center of the car and the extent of this offset is preferably made substantially one-half of the normal door opening used in ballasting operations with material of average 95 density, thereby obtaining with the stationary side hopper the same advantages which would be derived from the use of a double door car inasmuch as the door opening at this stage will be the equivalent of a V shaped hopper having both sides thereof 100 movable and of uniform travel. In this manner when the door "J" is opened to this average distance the center of the discharge opening will be substantially the center of the car and also the center of the roadbed. 105 By this offset hopper construction I attain in a cheaper construction the advantages embodied in a well known double door ballast car, i. e., placing the ballast in the center of the track. Center dump hoppers extending longitudinally of the car with the apex of the hopper located on the longitudinal center of the car have been used for a number of years, but owing to the fact that the discharge door opening is entirely confined to one side of the track, it is found that the ridge of ballast is deposited to one side, flooding the rail and causing derailment of 110 trains and entailing much lost time. A further advantage secured by my offset construction lies in the steep angle which the side "K" makes with the horizontal plane preventing adherence of the lading to the hopper side and thereby overcoming a defect which has hitherto rendered cars with 115 a hopper embodying a fixed side unreliable for center ballast work. It is well known to those having practical experience with center ballast work that it is customary for the operator controlling the discharge of the 120 125 130

load to gauge the door opening largely by the extent of the flow of material issuing from the discharge opening, inasmuch as it is impossible from his point of vantage, i. e., 5 the point of operation of the doors, to see the door itself. Consequently it is a matter of frequent occurrence that due to the insufficiency of the slope in the hopper floor the material arches in the car and does not flow 10 freely and the operator, in ignorance of this fact, seeing little or no flow of ballast, opens the door to such an extent that when rupture of the arch is effected there is an onrush of material which covers the rail and causes 15 a derailment of the moving car. I have guarded against this possibility by offsetting the stationary side of the hopper, thereby providing a slope at an angle considerably in excess of the angle of repose of the 20 material and greater than heretofore employed in cars of this type. Furthermore, I have provided automatic means as shown in Figure 1 to indicate to the operator the extent of the door opening at all times. This 25 includes a dial plate 78 secured to the car framing, an indicator 79 pivoted to the dial and connecting means 80 extending from the indicator and connected to the door.

The mode of operation is as follows: It 30 being desired to center ballast in a section of track, the loaded train of cars is brought into position and safety locking pawl disengaged from the ratchet 71 on all the cars. The lever of the forward car is then rotated 35 in a clockwise direction turning the worm and shaft and resulting in a gradual and controlled opening of the door and the train is set in motion. As the door opens the rod 80 is drawn inward, moving the indicator 79 40 and indicating on the dial scale the extent of the door opening. The opening of the door is then continued until the indicator on the dial shows that the normal door opening has been reached, in which position of the 45 door, the door opening is substantially equal on both sides of the longitudinal center of the car. If a very light run of ballast is desired, the train is moved at a higher speed and the doors of the various cars composing 50 the train opened in succession, i. e., immediately one car becomes empty the next one in the train is opened thereby forming a continuous ridge of ballast between rails.

It is often desired to deposit in one run 55 the maximum amount of ballast which can be safely placed between the rails without danger of derailing the cars or preventing a train from passing over the track. When such is the case, the train of cars is moved 60 into position and a number of the cars are opened to the normal position and the train is set in motion, moving at a very slow speed. The ballast in the various cars will discharge and gradually spread out until it assumes a position where the ridge of the bal-

last is free of the wheels and extends at an inclination made by the angle of repose of this material.

In order to make my load discharging car applicable to a great variety of uses 70 such as dumping coal and ore in center hoppers, I have rendered it possible for the door to open a greater extent than I have indicated as the normal amount, by providing a sufficient length of chain on the 75 sheaves to permit the door to swing to a vertical position.

In my former designs of center ballast cars employing double doors I have provided an I-beam longitudinal center sill 80 centrally disposed of the hopper for the purpose of sustaining the buffing and pulling stresses. In the construction of this type of cars with double doors the disposition of a center buffering member within the 85 hopper did not materially interfere with the discharge of the load, but with one of the sides of the hopper rigidly fixed I find it desirable to provide an unobstructed door opening in order to insure proper discharge 90 of the load. Consequently I have embodied in this invention a novel form of construction for transmitting the buffing and pulling strains from the centrally disposed 95 draft sills to the heavy side girders composed of intermediate and side sills which are widely spaced from the longitudinal center of the car in the manner already described.

Intermediate sill web 17 and bottom 100 angles are extended only as far as the body bolsters and included in the construction thereof while the top Z-bar 20 and the top angle 21 are extended longitudinally to the end of the car and secured to the end sill 105 cover plate 81. The end sill is preferably formed of a channel "C" to which is attached a striking plate 83. Connections between the draft sills, striking plate and end sills are effected by means of a box shaped 110 member 84. The box shaped member 84 is formed with horizontal flange 84^a secured to lower flange of the end sill and to the lower flange of the member G, both of which are substantially on the same plane. Vertically and longitudinally extending flange 84^b is secured to the draft sill and formed with a slot 84^c for the passage of a draft key (not shown). A vertical transversely disposed flange 84^d is secured to the striking plate 83. In this manner the end of the car is effectively braced against lateral, transverse, oblique and longitudinal strains. Disposed within the draft sills is the usual center block 85 and upright vertical portions are disposed between the draft sills and intermediate sills. Extending transversely across the car between the intermediate sills and secured thereto and to the vertical bolster portions and draft sills is 125 130

a bolster top cover plate 87. This plate is extended toward the end sill and secured to the diagonal members G which in this particular instance consists of a channel member. Extending transversely of the car and secured to the lower portions of the bolster vertical portions and to the draft sill and intermediate sills a wide bolster bottom plate 88 is disposed at each end of the car. Heretofore it has been customary to transmit draft shocks from the center or draft sills to the side sills, utilizing the bolster as a beam and thereby placing the bolster top and bottom plates under an un-
due strain. In such cars difficulty has been experienced due to rivets loosening and shearing after a period of service due to the fact that the bolster plates are called upon to perform the dual function of sustaining the vertical load and also transmitting draft shocks. Now in my invention I have devised a method whereby such strains are transmitted obliquely to the line of draft directly from the longitudinal center of car to the heavy side girders. The structure whereby this result is accomplished consists of the members G preferably of channel shape each having the upper flange secured to the end sill cover plate 81 and the lower flange secured to the box shaped member 84. A further connection is made between the diagonal member G and the end sill by means of a connecting member 89 securely anchoring the member G to the end sill. The members G extend within the longitudinal girders and are secured thereto by means of their upper and lower flanges connecting respectively to the top and bottom plates 26 and 27 of the girder. Furthermore, each of the members G extend co-extensively with the side sill for a considerable distance and is riveted to the web of the side girder thereby increasing the cross sectional area of this girder and greatly increasing its load carrying capacity.

Adjacent to the hopper I have provided floor portions 94 resting on nailing pieces 95 and supported by intermediate sill top angle 21 and side sill top angle 23. The floor is extended beneath Z-bar top flange 20 and maintained in position thereby and also protected from the plow. The opposite end of the floor is bolted to the side top angle by means of bolts 96. At each of the intermediate vertical stakes "P" I have provided a combination member 97 shown in Figure 2 having a horizontal flange extending from sill to sill and secured thereto and having a pressed U-shaped corrugation therein presenting a surface 97^a for the plow to ride on. The member is formed with a vertical portion extending upwardly and secured to the stake, the inner surface thereof 97^b constituting a rub plate. The connections 97 are disposed at intervals be-

tween the boards with the surfaces 97^a forming metallic wear plates on the side floor portions thereby saving the boards from the destructive effects of the plow. At the corner post I have disposed a combination rub plate 98 of a somewhat different construction as shown in Figure 4. This member consists of a horizontal portion 98^a, upright rub plate portion 98^b and a reinforcing brace 98^c pressed therein stiffening the angle. 75

The car is convertible from a center dump car to a flat gondola car by the fact of being provided with convertible swinging bottom sections M loosely pivoted to the intermediate sills. The swinging sections are provided with stiffeners 101 and reinforcing strap 102 forming flat bottom portions for the car in one position and being movable to form inclined hopper portions in another position as shown in Figure 1. In the present instance I have increased the length of the swinging side portions for a considerable distance beyond the ends of the lower fixed hopper portion whereby the distance between the movable ends N of the car may be increased with a consequent increase in the capacity of the car as a hopper and without any resultant increase in the length of the car between trucks. In order to make the car entirely self-discharging I have provided a flap forming an inclined shedding plate O extending from the movable end to the fixed lower hopper, thereby forming an upward extension of the lower hopper end wall. The flap preferably consists of a sheet metal plate reinforced with corrugations or stiffeners 103 and having its edges 104 sheared to conform with the slope of the hopper sides. The upper portion is preferably bent in the form of a loop 105 thereby providing a combined reinforcement and hinge through which a continuous rod 106 passes. The shedding member is maintained in position by means of a rail member 107 on the movable end. When the car is converted into a gondola as shown in Figure 5 the flap is moved to a vertical position, the hinge rod sliding upwardly in the slot formed by the rail and the corrugation in the flap fitting over the rails. In this manner the flap occupies very little place and is secured in its vertical position preferably by means of bolts 108. 115

With the convertible floor sections M in the horizontal position and the movable ends N removed from the car, unloading is effected by means of an unloading plow through the side doors S and for the purpose of effectively supporting the side doors I have provided a novel frame work consisting of intermediate stakes P each formed of two bulb angles 109 placed back to back and anchored together and secured to the side girders directly by means of rivets and also through the medium of connec- 125 130

tion 97. At the corner posts I have disposed two bulb angles 110 and 111 in the same direction, spacing them apart sufficiently to form the stiles of a ladder to which ladder treads 112 are attached and at the lower portion thereof sill step 113, thereby providing a safe ladder immediately adjacent the end of the car and wherein a man is fully protected from the swinging side door and discharging load.

By means of stake member 111 which has its web 111^a disposed transversely of the car and riveted to the end sill C and its wide flange secured to the side sill A, a very strong anchorage is thereby obtained for the lower portion of the corner post. Above the side sill the bulb angles 110 and 111 are secured to the combination rub plate 98 which extends from one to the other of these members and is riveted thereto. Above the combination rub plate a plate 114 completes the corner post construction. The top rail R member consists of a bulb angle 115 and a wooden beam 116. The vertical flange of the bulb is secured to the stakes P by rivets and gusset 117 and also riveted to the corner posts. Swinging side doors S are formed with battens 118 and hinges 119 and swing from U bolts 120 supported by the top rail. Door locking mechanism consists of a longitudinally extending shaft 120 having arms 121 fixed rigidly thereto adapted to engage the battens 118. Shaft supporting bearings 122 are riveted to the stakes and operating lever arm 123 rigidly fixed to the shaft and disposed at the end of the car.

I have herein shown and described what I now consider the preferred manner of carrying out the invention, but the same is merely illustrative and I contemplate all changes and modifications that come within the scope of the claims appended hereto.

I claim:

1. In a load discharging car adapted to deposit ballast between rails, the combination with longitudinally extending sills disposed on each side of a hopper composed of oppositely inclined sides, one of such sides having a pivoted door and the opposite side thereto being stationary, gussets connecting the stationary side and one of the sills, bearings carried by the gussets, a rotary shaft mounted in the bearings and a series of flexible connections between the shaft and door and means for rotating the shaft; such means being adapted to engage the shaft intermediately of the ends thereof and intermediately of some of the said flexible connections.
2. In a load discharging car adapted to deposit ballast between rails, the combination with longitudinally extending sills disposed on each side of a hopper composed of oppositely inclined sides, one of such sides having a pivoted door and the opposite side

thereto being stationary, a rotary shaft mounted between the said stationary side and side sill, flexible connections between the shaft and door, and means for rotating the shaft, such means operating in a direction substantially at right angles to the movement of the said rotary shaft, and being adapted to engage the shaft intermediately of the ends thereof.

3. In a load discharging car adapted to discharge ballast between rails, the combination with a supporting framework of a longitudinally extending hopper having oppositely disposed sides, one of such sides having a pivoted door and the opposite side thereto being stationary and means for opening and closing the door; such means including a rotary shaft and a worm and gear, adapted to engage said shaft intermediately of the ends thereof.

4. In a load discharging car adapted to discharge ballast between rails, the combination of a supporting framework, a longitudinally extending hopper having oppositely disposed sides, one of such sides having a pivoted door and the opposite side thereto being stationary, beams extending transversely of the hopper, gussets connecting such beams and sills; a rotary shaft mounted in the framework of the car, flexible connections between the shaft and door, means for rotating the shaft and moving the door, such means comprising a worm and gear mounted in a housing secured to one of the aforesaid gussets connecting the stationary hopper side and sill, said worm and gear being adapted to engage said shaft intermediately of the end thereof and intermediately of some of said flexible connections.

5. In a load discharging car, in combination, a lower fixed central hopper below the floor level, a member disposed in a substantially vertical plane above the floor level and spaced outwardly from the end of the lower hopper and constituting a car end wall and a loosely mounted inclined shedding member adapted to bridge the space between said end wall and lower hopper.

6. In a load discharging car, the combination in a convertible car of a lower hopper portion, a car end member movable in position to form the upper end wall of the car, and an inclined member adapted to extend from the said upper end wall to the lower hopper portion whereby the dumpable length of the car will be increased without increase in length of dump door opening.

7. In a load discharging car, the combination in a convertible car including longitudinally adjustable end walls, a longitudinal dumping hopper, doors swingingly mounted along the upper edges of the said hopper and arranged to form in one position a part of a horizontal floor of the car and to be

- swung upwardly from a horizontal position to form a portion of a hopper inclined side, the upper portion of the said hopper as formed by the swinging sections being of 5 greater length than the lower portion and a loosely mounted inclined member extending from said adjustable end walls to the fixed hopper.
8. In a load discharging car having an 10 end wall, a flap hinged to said end wall and movable from a vertical position to form an inclined end wall for the said car.
9. In a load discharging car including side walls inclined to form the sides of a 15 hopper, an end wall, a flap pivotally mounted on the said end wall and adapted to assume an inclined position and adapted to be supported in such position by the inclined sides of the hopper.
10. In a load discharging car including a lower fixed hopper having sloping side walls and sloping end walls, sloping convertible sections forming sloping side walls above the floor line of the car and an inclined shedding member adapted to overlie the said convertible sides and forming an upper extension to the said lower hopper end wall.
11. In a load discharging car provided 30 with a central dumping opening, end walls having inclined shedding members secured thereto whereby the dumpable length of the car is increased, said shedding members being reinforced with corrugations.
12. In a load discharging car provided 35 with a central dumping opening, end walls having inclined shedding members slidingly mounted on the said walls and adapted to increase the dumpable length of the car.
13. In a load discharging car, provided 40 with a fixed lower hopper having an inclined end wall, the combination of a longitudinally movable end wall, a series of rails spaced from the said end wall and secured thereto, a flap composed of sheet metal and having the upper edge thereof bent in the form of a loop, a rod passing through said loop and interposed between the said rail and end wall, the said flap being adapted to form an extension to the said 45 inclined lower hopper end wall and thereby increase the dumpable length of the car.
14. In a railway car, convertible from a center dump hopper to a gondola car, the 50 combination with a longitudinally movable end adapted to assume in one position the end of a gondola car and adapted to assume in another position the end of a center hopper car, a flap pivotally mounted on the
- said end adapted to assume an inwardly and 60 downwardly sloping position with the car in center hopper service and a substantially vertical position when the car is in gondola service and means for securing the flap in such vertical position. 65
15. In a ballast distributing car of the convertible type, a center discharge hopper and doors therefor, side discharge doors, vertical car sides and end walls and horizontal car floor sections in combination 70 with movable side and end sections which in an inclined position complete the wall of a center discharge hopper car inoperative for side dumping; or in alternate positions form a flat floor gondola car for side dumping inoperative for center dumping. 75
16. In a ballast distributing car of the convertible type, vertical car sides and end walls and horizontal floor sections, a longitudinal center discharge hopper and doors 80 therefor, longitudinal side discharge doors and movable side and end members; the said movable side members forming a part of the side hopper walls of a center discharge hopper car or a horizontal section of 85 the car floor of a gondola car; the said movable end section forming a part of an inclined end section of the center discharge hopper car or a part of the vertical end for a side discharge gondola car. 90
17. In a load discharging car adapted to deposit ballast between rails, the combination with longitudinally extending sills disposed on each side of a hopper composed of oppositely inclined sides, one of said sides 95 having a pivoted door; a rotary shaft; a series of flexible connections between the shaft and said pivoted door; and means for rotating said shaft, said means being adapted to engage the shaft intermediately the 100 ends thereof and intermediately of some of said flexible connections.
18. In a load discharging car, in combination, a central hopper extending longitudinally of the car, substantially level floor 105 portions at each side thereof composed of boards, metallic wear plates secured to the side stakes of said car and having portions disposed between said floor boards and forming a portion of said side floor. 110
- In witness that I claim the foregoing I have hereunto subscribed my name this 9th day of August, 1923.

ARGYLE CAMPBELL.
